UNITED STATES PATENT OFFICE.

MERRITT F. POTTER, OF KANEVILLE, ILLINOIS.

IMPROVEMENT IN COMBINED SYRINGES, SHOWER-BATHS, AND DISINFECTING APPARATUS.

Specification forming part of Letters Patent No. **152,046**, dated June 16, 1874; application filed December 17, 1873.

To all whom it may concern:

Be it known that I, MERRITT F. POTTER, of Kaneville, in the county of Kane and State of Illinois, have invented a Syringe Combined with a Shower-Bath and Disinfecting Apparatus, of which the following is a specification:

The subject of my invention is, first, a device by which I form an exhausted air-chamber in a syringe-bag, consisting of a closed and collapsing membranous reservoir. Another part of my invention consists of a device by which I close and open the combined inlet and outlet tube of my syringe. Another part of my invention consists in my method of holding the tube in contact with the vessel containing the liquid. Another part of my invention consists of a device for irrigating the body. Another part of my invention consists of a device for suspending my syringe-bag without requiring a nail. Another part of my invention consists in a portable hydraulic disinfecting apparatus.

Figure 1 of the drawings shows the apparatus arranged to disinfect a room. Fig. 2 shows the stop-ring. Fig. 3 is the hook by which the bag is suspended. Fig. 4 is the curved tube used for irrigation; and Fig. 5 shows the bag being filled through the tube, which serves as a siphon.

In Plate I, A represents a closed-reservoir syringe-bag lying upon its side. C is a siphon-inlet tube. D is a vessel of liquid standing on a platform above the bag. E is a small ring on the tube C, which is movable. B B' are two handles or thumb-pieces attached to the opposite sides of the bag. The bag A is naturally collapsed, with no power to fill itself. To fill it, a current of liquid must be started from the vessel D through the siphon-inlet tube C. This is done as follows: I take hold of the two handles, one in each hand, and draw them apart, separating the two opposite sides of the bag. A partial vacuum is thus formed in the tube and bag, to supply which the water flows in, and continues to flow until the bag is filled.

The second part of my invention, by which I close and open the discharge-tube C, is as follows: F is a ring, noosed by a cord to the tube C, as seen in Figs. 1 and 2. To close the tube, I double it upon itself, and slide the ring

upon the bent part, as seen in Fig. 2, Plate I. To open the tube, I have only to put it upon the stretch. The ring slips off, and hangs connected to the tube by the tape G. During the process of filling the tube C is kept from slipping off from the edge of the vessel D by the small movable ring E, which can be so adjusted on the tube to vessels of different sizes as to be placed just inside the edge of the vessels, as seen in the figure.

I also combine a shower-bath with my invention, as follows: Having filled the bag and suspended it at a proper altitude, I insert in the end of the rubber tube the curved tube K, having a small orifice at its point. L is a flexible hook attached to the curved glass tube. When the tube C is hanging vertically, and is extended its whole length, I insert the sharp-pointed tack-nail into the wall or window-casing, about two inches below the end of the hook L. Taking hold of the rubber tube C, I stretch it so as to hook the wire L over the tack where it enters the wood. The outlet of the tube K may then be opened, and the liquid will spirt obliquely upward in a divergent jet, and, when it turns downward, will fall in a copious shower, as if propelled from a rose with many jets.

It is frequently desirable to suspend my instrument in a room where a nail or hook would not be allowed. I have therefore constructed the grapple-hook M, and noosed over it the loop N of the bag. This hook terminates in a sharp vertical point when in position, and can be hooked to the edge of a shelf or top of a window-casing, on which the bag hangs, as if on a pivot, with no danger of losing its hold. O is an eyelet at the lower part of the hook, into which I can insert the sharpened point of a stick three or four feet long, and hang it to the top of a window-casing twelve or fourteen feet above me while standing on the floor.

The last part of my invention is an apparatus for diffusing disinfecting liquids throughout apartments, and over the persons of those who are liable to carry contagious diseases in their clothing. P is a rose with many minute foramina, so drilled that the liquid escaping through them will pass in many fine divergent jets. If I now take the bag filled with the disinfecting solution in the right hand and ele-

vate it, and take the rose in my left hand and depress it, holding the perforated part upward, and compress the bag in the right hand, the liquid will be forcibly ejected in all directions, and the largest room can be entirely covered in a few seconds with the expenditure of a very small amount of liquid.

I claim—

1. In combination with the elastic self-collapsible bag A and elastic tube C, the two handles B forming a part of the same for separating the sides of the bag, to produce a partial vacuum, and allow the tube E to act as a siphon and fill the same, all arranged as set forth:
2. The combination of the stop-ring F with the automatic collapsing bag A and elastic tube C, all as and for the purposes set forth.
3. The adjustable ring E, combined with the bag A and tube C for retaining the latter on

the edge of a vessel while serving as a siphon for filling the bag, all as and for the purposes set forth.

4. The attaching-hook M, when of the form shown, and composed of a single wire, in combination with the bag A and tube C for attaching the bag by means of a pointed rod to any projection in the room, so that the apparatus may serve as an irrigator, all as and for the purposes shown.

5. In combination with the self-collapsing bag A and elastic tube C, the rose P, arranged to be forced within the end of the tube, forming a disinfecting apparatus, as and for the purpose set forth.

MERRITT F. POTTER.
